METHOD OF AND APPARATUS FOR COVERING ARTICLES WITH SHEET MATERIAL

William P. Devine, Boston, Mass., assignor to
United Shoe Machinery Corporation, Paterson,
N. J., a corporation of New Jersey

Application April 3, 1928, Serial No. 267,116
Renewed March 9, 1933

31 Claims. (Cl. 12—42)

This invention relates to a method of and apparatus for covering articles with sheet material. The particular embodiment of my invention illustrated in the drawings and set forth in the specification is particularly adapted for covering wood heels with celluloid, but I wish it to be understood that I do not limit my invention to this particular embodiment as the same may be utilized for covering articles other than heels for boots and shoes, and in the particular embodiment of the invention, the sheet material for covering the heels may be celluloid, leather or cloth.

The object of the invention is to provide a method and apparatus whereby articles may be covered with sheet material rapidly and efficiently.

In carrying my invention into practical operation for the covering of wood heels with celluloid, the celluloid is first softened by placing it in a mixture of alcohol and water, preferably three parts of alcohol to 1 part of water and allowing it to stay in this mixture until it becomes softened, which generally takes about twenty minutes. The sheet of celluloid used for covering the heel is preferably cut out of the proper shape to cover the outer face of the heel and to project over around the edges of the heel. Adhesive material is placed on the heel around the edges, the celluloid being then placed upon a folding member, preferably consisting of a band of flexible or elastic material. Rubber has been found to be practicable for this purpose.

The heel is placed upon a holder with the back of the heel underneath and the breast and seat of the heel resting against the lower edge of said holder, there being means to hold the heel upon the holder. The holder of the heel is placed in a press, which may be operated by any suitable power. The heel is then pushed downwardly until the back of the heel engages the celluloid blank and upon further downward movement of the holder, the celluloid blank, together with the elastic band upon which it is positioned, are formed around the outer face of the heel and the celluloid is folded over the edge of the seat and the tread and breast portions of the heel. The heel holder is then moved upwardly and the heel taken out of the machine with the celluloid cover smoothly attached to the heel over its entire outer face and projecting slightly over and into contact with the edge portion of the seat and tread and breast of the heel.

The invention consists in the method of performing the foregoing operation and in the apparatus by which the method may be carried into practical operation, all as hereinafter fully set

forth in the specification and particularly pointed out in the claims.

Referring to the drawings:

Figure 1 is a side elevational view partly in section of the illustrated apparatus for covering 60 heels.

Fig. 2 is a plan view of the lower portion of the apparatus parts of which have been broken away.

Fig. 3 is a sectional view of the apparatus taken 65 along line 3—3 of Fig. 1.

Fig. 4 is a sectional view similar to Fig. 1 illustrating the parts of the apparatus in their relative positions when the heel has been covered.

Fig. 5 is a side elevational view of the apparatus mounted on a press of suitable construction. 70

Fig. 6 shows a side elevational view of a modified heel holder and a heel carried thereby.

Fig. 7 is a transverse sectional view showing a modified form of folder or band and the members 75 which fold sheet material upon the band over the edges of the heel.

Fig. 8 is a vertical section of a heel after it has been covered in the illustrated machine.

In the drawings, referring to Figs. 1 to 5 inclusive, 10 is the frame of a press upon which the folding apparatus is mounted, and consisting of a lever 11 pivoted at 12 to the frame 10 and connected by a link 13 to toggle links 14 and 15, the link 14 being pivoted at its outer end to an adjustable stud 16, and the link 15 being pivoted at its outer end to a slide 17 to which a reciprocatory motion is thus imparted.

The slide 17 carries a holder 18 which projects into a slot 19 (Figs. 3 and 4) in the slide 17 and 90 is adjustably held in said slot 19 by a screw 20 so that the holder may be adjusted toward or away from the front of the machine. The holder 18 is provided in its lower edge with a slot 21 into which the front edge 22 of the attaching face or 95 the seat of the heel projects, as illustrated in Fig. 3 wherein 23 is the heel, the breast 24 of the heel bearing against the lower edge of the portion 25 of the holder 18 on one side of the recess 21 and a portion 26 of said holder bearing against 100 the seat of the heel.

In order to insure accuracy in positioning the heel upon the holder and to enable the operator readily to place the heel in proper position, one or more pins 27 may be used, these pins being secured to the holder 18 and projecting into recesses formed in the breast of the heel 23. A band or pad 28, which is preferably of rubber or some elastic material and which may be referred to as a folder, is clamped at one end thereof by 110

a plate 29 to another plate 30 provided with ears 31 having holes 32 therein and through which upright pins 33 project, the pins 33 having heads 34 thereon, and being integral with a cross bar 35 of a T-shaped member 36, a shank 37 of said T-shaped member projecting through the end 38 of a frame 39 and being adjustably fastened in said frame by a screw 40 (Fig. 1). The frame 39 consists of a base 41, two side pieces 42 and 10 an end piece 38. The opposite end of the elastic folder or band 28 is clamped to a cross piece 44 by a clamp plate 45. By adjusting the shank 37 in the end 38 of the frame 39 any slack in the belt may be taken up. Thus the two ends of the 15 elastic band 28 are held while the opposite sides of the said band are left free as will be seen by reference to Figs. 2 and 3.

Side plates 46 are fastened to the tops of the side frames 42, thus constituting a guideway 20 therebetween to receive the band 28. The band 28 is convexly curved midway of its length at 47 as illustrated in Fig. 3 in order to approximately fit the curved outer face 48 of the heel 23. Slidably mounted on the side frames 42 in ways 49 are a 25 pair of slides 50 and 51 which are spaced apart to form a chamber 52 between their adjacent ends 53 and 54. The adjacent ends 53 and 54 are provided along their lower edges with horizontal flanges 55 and 56 which form a support for a 30 cushion 57 of flexible or elastic material, such as rubber. The adjacent faces of the ends 53 and 54 are each provided with a section of elastic sheet material 58, the ends 53 and 54 and also the sections 58 imbedded therein are disposed at an 35 angle to each other, and to a central vertical plane extending through the holder 18, so that the ends 53 and 54 of the slides and the sections of elastic material 58 imbedded therein converge toward each other from the front to the rear of the 40 casting 39. The median vertical plane of the chamber 52 between the ends 53 and 54 is approximately coincident with the median plane of the holder 18. A plate 59 is fastened to the side plates 42 of the frame 39 by screws 60, and this plate 45 has an aperture 61 extending therethrough and having a flange 62 extending therearound as illustrated in Figs. 1 and 3, and this aperture is of the outline corresponding to the outline of the blank of celluloid which is to be applied to the 50 outer face of the heel 23. Approximately one-half of the aperture 61 is shown in Fig. 2 as the positioning plate 59 is broken away in that view. A blank 63 of celluloid is placed within the aperture 61 and rests upon the flange 62. Although 55 the illustrated machine is provided with the plate 59 it will be understood that such plate, if desirable, may be removed, the cover being supported upon the band or pad 28.

The slide members 50 and 51 are each provided 60 upon their adjacent ends with anti-friction rolls 64 and a reciprocatory motion is imparted to the slide members 50 and 51 by levers 65 and 66 respectively. These levers are connected to the slide members by pins 67 and their outer ends 65 are provided with rolls 68, the said levers being pivoted at 65' and 66' to the frame 39. A rocking motion is imparted to the levers 65 and 66 by cam plates 69 which are adjustably fastened by screws 70 to the slide 17. Stop screws 71 and 72 limit the distance to which the slides 50 and 51 respectively will be moved apart by a spring 73 which connects the outer ends of the levers 65 and 66 together.

The general operation of the mechanism hereinbefore specifically described and illustrated in

Figs. 1 to 5 inclusive is as follows: The operator applies adhesive to the edges of the heel 23 and positions it upon the holder 18 as illustrated in Fig. 3 and it will be noted that the edge of the tread of the heel at the rear portion thereof as at 74 and of the seat of the heel at the rear portion thereof as at 75 are tangential to a plane A—A, Fig. 3, the plane A—A being approximately horizontal and approximately parallel to the upper face of the band 28. A blank of celluloid 63, which has been previously softened, is placed within the aperture 61 resting upon the flange 62 of the plate 59. The parts of the machine are in the relative positions illustrated in Figs. 1, 2 and 3. The operator now steps on a treadle, not shown in the drawings, which rocks the lever 11 and through the links 13, 14 and 15 the slide 17 is caused to move downwardly, together with the heel 23 and its holder 18, and also the cam plates 69. 80

This downward movement of the holder 18 brings the rear portion of the outer face of the heel into contact with the blank 63 and it will be noted that the lower edge of the heel and the upper edge of the heel at 74 and 75 respectively will simultaneously engage the upper surface of the blank, which is at that time resting on the plate 59. Further downward movement carries the blank and the heel 23 downwardly into the chamber 52, causing the band 28 and the blank 63 to be wrapped around the outer face of the heel 23 with the band 28 under tension, and bent in a U shape by reason of extending over the rolls 64. Finally the cam plates 69 engage the cam rolls 68 to rock the levers 65 and 110 66 apart at their outer ends, thus moving the slide members 50 toward each other and bringing the elastic sections 58 on the adjacent faces of said slide members into contact with the U-shaped portion of the band as illustrated in Fig. 115 4, thus forcing the band and the blank inwardly and causing the edge of the blank to be turned over the edges of the heel, both on the heel seat and on the tread face of the heel, as illustrated in Fig. 8. 120

The elastic band where it passes around the back portion of the heel as illustrated in Fig. 4 will be pressed against the cushion 57. The celluloid cover now having been applied to the heel, the operator releases the treadle, the slide 17 moves upwardly carrying the holder 18 and the heel 23 with it, and the slide members 50 and 51 are separated by the resilience of the elastic band 28 and also by the spring 73 until they assume the positions illustrated in Fig. 1 where the slide 50 is shown abutting against the stop screw 71, and the slide 51 is shown abutting against the stop screw 72. The operator then removes the heel from the holder 18. It will be seen that by adjusting the stop screws 71 and 72, that the slides 50 and 51 will be accurately positioned equidistant from the median plane 3—3, Fig. 1. 130

It has been found that the angle of an inclined plane which is tangent to the edge of the tread and of the seat of the heel on the side portion of the heel is approximately 12°, and that is the angle of each of the faces of the end portions 53 and 54 to the median plane 3—3. It is essential that the proper space to obtain the best results should be allowed between the adjacent faces of the ends 53 and 54 of the slides 50 and 51 and the outer face of the heel as it is pushed down into the chamber 52, and this distance between the heel and the said adjacent faces of the slides may be varied by adjusting the holder 18 forward- 140 145 150

ly or backwardly upon the slide 17 and then fixing the plate in position in the slot 19 by means of the screw 20.

The elastic band 28 may be removed and a new band inserted in its place by removing the clamp plates 29 and 45, and securing it in place by means of the clamp plates.

Instead of supporting the heel upon the holder 18 as hereinbefore set forth and illustrated in Fig. 3, the heel 23 may be supported upon a holder 18' which is provided with a recess 21', the tread projecting into a recessed portion 76 in the lower edge of the holder 18', while the seat of the heel is held in position by a pin 77 on the lower end 15 of a latch 78 pivoted at 79 and actuated by a pin 80 and spring 81. This means of positioning and locking the heel upon its support obviates the necessity of boring a hole, or holes, in the breast

20 It will be understood that while I have de-
scribed the band 28 as an elastic band, and pref-
erably made of rubber, the same may be con-
structed as illustrated in Fig. 7, that is, with the
central portion of the band 28' made of rubber
25 82 and the end portions 83 and 84 made of other
materials such as woven fabric, in which case
the ends of the band are coiled upon and fastened
to rolls 85 and 86. These rolls are rotatably
30 mounted upon shafts 87 and 88 and each is joined
to its respective shaft by a spring 89, one end of
which is fastened to the shaft, the other to the
inside of the roll in a manner well known to
those skilled in this art, whereby a torsional strain
35 is applied to the spring to wind it up when the
central portion of the belt is pushed downward-
ly by the heel as hereinbefore described in rela-
tion to the form of belt illustrated in Figs. 1 to
4 inclusive.

4 inclusive.

Each of the shafts 87 and 88 has a ratchet 90 fast thereto, the ratchet being shown attached to the shaft 87 only in Fig. 7, but a like ratchet is fastened to the shaft 88 at the opposite end of the shaft from that in which Fig. 7 is viewed. A pawl 91 engages each of the ratchets and is illustrated on one of the ratchets in Fig. 7. The shafts 87 and 88 are rotatably mounted upon ears 92 and 93 which are formed on the sides '42' of the frame 39'. The springs 89 tend to keep the band 28' taut at all times. The tension upon the springs 89 may be increased by winding up the shafts 87 and 88, or either of them. Instead of a plate, such as 59 hereinbefore described with relation to Figs. 1 to 4 inclusive, the blank of celluloid may be positioned within a ridge or flange '94 forming a part of the central rubber portion 82 of the band 28'. This ridge is molded in the rubber when the same is constructed and is of a contour like that of the cover which is to be applied to the heel.

60 If it is desired to center the belt relatively to the holder and the heel so that the blank will be correctly positioned thereon, it may be done by adjusting the belt in one direction or the other simply by releasing one of the ratchets 91
65 and turning one of the shafts 87 or 88 as may be desired until the ridge 94 of the portion 82 of the belt is correctly positioned relatively to the heel which is to be covered.

In the operation of the machine with the belt illustrated in Fig. 7, the cover is applied to the heel in substantially the same manner as hereinbefore described, that is, the central portion 82 of the rubber is wrapped around the heel with the cover for the heel interposed between the portion 82 and the heel, and the rubber itself can

yield and conform to the shape of the heel in such manner as to smoothly and closely apply the cover to the heel with the desirable results attained by the embodiment of my invention hereinbefore described and illustrated in Figs. 1 to 5 inclusive. The central portion 82 of the band may be attached to the end portions 83 and 84 in any suitable manner as by rubber cement and vulcanization.

I claim:

1. The method of covering heels with sheet material which consists in causing a heel to be advanced toward and pressed against a piece of said material while the latter is resting against a band of elastic material in a predetermined position relatively to said heel while holding the opposite ends of said band stationary whereby the latter is caused to be wrapped around the outer face of the heel under tension, and then folding the sheet material over edges of the heel with said elastic material.

2. The method of covering heels with sheet material which consists in causing a band of material with a piece of sheet material positioned thereon in a predetermined position relatively to said heel to be wrapped around the outer face of the heel while holding the opposite ends of said band with the said sheet material interposed between said wrapping material and the heel, and then folding the sheet material over edges of the heel with said elastic material. 100

105

3. The method of covering a heel with sheet material which consists in applying adhesive to the heel, then causing a band of material with a piece of sheet material positioned thereon in a predetermined position relatively to said heel to be wrapped around the outer face of the heel while holding the opposite ends of said band with the said sheet material interposed between said wrapping material and the heel, and then folding the sheet material over edges of the heel with said elastic material. 110 115

4. An apparatus for covering heels with sheet material having, in combination, a support adapted to have a heel positioned with its breast in contact therewith, a yielding folder, means to adjust said support relatively to said folder, a pair of members spaced apart on which said folder rests, and means to cause relative movement between said support with a heel positioned as aforesaid and the folder, whereby a piece of sheet material positioned on said folder and interposed between said folder and heel may be applied to said heel, thrust into the space between said members and folded around the outer face of said heel.

5. An apparatus for covering heels with sheet material having, in combination, a support adapted to have a heel positioned with its breast in contact therewith, a yielding folder band, means to hold opposite ends of said band, means to move one of said members relatively to the other, whereby a piece of sheet material positioned on said folder band in predetermined relation to said heel may be folded around the outer face of said heel, and means to fold said sheet material over edges of said heel.

6. An apparatus for covering heels with sheet material having, in combination, a support for a heel, one face thereof having a recess to receive a portion of the upper edge of said heel while contacting with the breast and seat of the heel on opposite sides of said recess, a yielding folder, and means to move one of said members relatively to the other, whereby a piece of sheet material inter-

posed therebetween may be folded around the outer face of a heel mounted on said support.

7. An apparatus for covering heels with sheet material having, in combination, a support for a heel, one face thereof having a recess to receive a portion of the upper edge of said heel while contacting with the breast and seat of the heel on opposite sides of said recess, means to position said heel on said support, a yielding folder, and means to move one of said members relatively to the other, whereby a piece of sheet material interposed therebetween may be folded around the outer face of a heel mounted on said support.

8. An apparatus for covering heels with sheet material having, in combination, a support for a heel, an elastic band, means to adjust the tension on said band, and means to move one of said members relatively to the other, whereby a piece of sheet material interposed therebetween may be folded around the outer face of a heel mounted on said support.

9. An apparatus for covering heels with sheet material having, in combination, a support adapted to have a heel positioned with its breast in contact therewith, an elastic band, means to move one of said members relatively to the other, whereby a piece of sheet material interposed therebetween and positioned on said elastic band in predetermined relation to said heel may be brought into contact with and folded around the outer face of said heel, and means to press the elastic band over edges of the heel whereby the edges of said sheet material may be folded over the edges of said heel.

10. An apparatus for covering heels with sheet material having, in combination, a support adapted to have a heel positioned with its breast in contact therewith, an elastic band, means to move one of said members relatively to the other, whereby a piece of sheet material interposed therebetween and positioned on said elastic band may be brought into contact with and folded around the outer face of a heel mounted on said support, a pair of presser slides spaced apart to receive said heel therebetween, and means to move said pressers relatively to said heel whereby edges of the elastic band may be folded over edges of the heel with said sheet material therebetween.

11. An apparatus for covering heels with sheet material having, in combination, a support for a heel, an elastic band, means to move one of said members relatively to the other, whereby a piece of sheet material interposed therebetween may be folded around the outer face of a heel mounted on said support, and a pair of presser slides spaced apart to receive said heel therebetween, and means to impart a reciprocatory motion to said slides whereby edges of the elastic band may be folded over edges of the heel with said sheet material therebetween.

12. An apparatus for covering heels with sheet material having, in combination, a support for a heel, an elastic band in alignment therewith, means to impart a reciprocatory motion to said support, whereby a piece of sheet material interposed therebetween may be folded around the outer face of a heel mounted on said support, a pair of presser slides spaced apart to receive said heel therebetween, and mechanism actuated by said support reciprocating means to impart a reciprocating motion to said slides, whereby edges of the elastic band may be folded over edges of the heel with said sheet material therebetween.

13. An apparatus for covering heels with sheet material having, in combination, a support for a

heel, an elastic band, means to move one of said members relatively to the other, whereby a piece of sheet material interposed therebetween may be folded around the outer face of a heel mounted on said support, a pair of presser slides spaced apart to receive said heel therebetween, yielding material on the contacting faces of said slides, and means to impart a reciprocatory motion to said slides, whereby edges of the elastic band may be folded over edges of the heel with said sheet material therebetween.

14. An apparatus for covering heels with sheet material having, in combination, a support for a heel, an elastic band in alignment with said support, a pair of members upon which said band rests, said members being spaced apart to receive said heel and band therebetween, the adjacent faces of said members converging, and means to move said support to bring a heel thereon into contact with sheet material on said band and thereby force said band and sheet material between said members whereby said sheet material positioned on said band may be folded around the outer face of said heel.

15. An apparatus for covering heels with sheet material having, in combination, a support adapted to have a heel positioned with its breast in contact therewith, an elastic band in alignment with said support, a pair of members upon which said band rests, said members being spaced apart to receive said heel and band therebetween, means to move said support to bring said heel into contact with a piece of sheet material positioned on said band in predetermined relation to said heel and force said heel between said members, and means to move said members relatively to each other thereby to force the edges of said sheet material over the edges of said heel.

16. An apparatus for covering heels with sheet material having, in combination, a support for a heel, an elastic band, means to move one of said members relatively to the other, whereby a piece of sheet material interposed therebetween may be folded around the outer face of a heel mounted on said support, a pair of presser slides spaced apart to receive said heel therebetween, an anti-friction roll rotatably mounted on each of said slides at their forward ends, and means to impart a reciprocatory motion to said slides whereby edges of the elastic band may be folded over edges of the heel with said sheet material therebetween.

17. In an apparatus for covering heels with sheet material, a holder for a heel, the underside of which is provided with a recess to receive the upper edge of a heel, while the said underside of the holder bears against the breast and seat of the heel.

18. In an apparatus for covering heels with sheet material, a holder for a heel, the underside of which is provided with a recess to receive the upper edge of a heel while the said underside of the holder bears against the breast and seat of the heel, and means to hold and position said heel on said holder.

19. An apparatus for covering heels with sheet material having, in combination, a flexible folder, a holder for a heel, means to position said heel on the holder with its rear, upper and lower edges tangent to a plane approximately parallel to said folder, and means to move said holder with a heel thereon toward said folder until said rear edges contact with a piece of sheet material superimposed on said folder.

20. An apparatus for covering heels with sheet

- material having, in combination, a holder for a heel, a yielding band, a portion of said band being in alignment with said holder and convexly curved transversely thereof on its upper face, 5 and means to move said holder with a heel thereon toward said band until the heel contacts with a piece of sheet material positioned on the convex portion of said band.
21. An apparatus for applying a cover to the 10 outer surface of a heel having, in combination, a band of flexible material, means to hold opposite ends of said band, a plunger in alignment with said band, means to move said plunger toward said band, a contact member on the bottom 15 of said plunger adapted to engage the top of a heel, and a contact member on the bottom of said plunger adapted to engage the breast of said heel.
22. A heel covering machine having, in combination, means for supporting a heel, a pair of spaced members, a resilient pad in engagement with said members and constructed and arranged to support a heel cover in predetermined relation with respect to the heel supporting means, means 25 for moving the support to cause the heel to be moved relatively to the pad thereby to apply a portion of the cover to the heel, and means for causing the members to move relatively to the support to apply other portions of the cover to the heel.
23. A heel covering machine having, in combination, a support provided with abutments constructed and arranged to engage the attaching and the breast faces of a heel respectively, a 30 pair of members spaced from each other to form an opening of varying width, an elastic pad supported by said members and constructed and arranged to support a heel cover, means for moving the support to force a heel against the pad thereby applying the cover to a portion of the heel, and means to move the members relatively to the support for applying the cover to other portions of the heel.
24. A heel covering machine having, in combination, means to support a heel, a pair of members spaced from each other, an elastic pad supported by and constructed and arranged to bridge the gap formed between said members and to support a cover, mechanism for moving the support relatively to the pad to force a heel against the cover on the pad and into the spaced formed between said members thereby to apply the cover to a portion of the heel, and mechanism for moving the members relatively to the support to apply other portions of the cover to the heel.
25. A heel covering machine having, in combination, a resilient pad provided with a convex surface for supporting a heel cover, a support for a heel, means for moving the support relatively 45 to the pad to force a concave surface of the heel against a cover which is supported by the convex surface of the pad thereby to apply portions of the cover to said surface of the heel.
26. A heel covering machine having, in combination, a resilient pad provided with a convex surface for supporting a heel cover, members for supporting the pad, said members being spaced from each other to form a recess, a support for a heel, means to move the support relatively to the pad for forcing the heel against the
- cover to cause a portion of the pad to be forced into the recess and to apply the cover to curved portions of the heel, and means to move the members relatively to the support for applying the cover to other portions of the heel.
27. A heel covering machine having, in combination, a support constructed and arranged for engagement with the attaching, the breast, and the tread faces of a heel, a pair of members spaced from each other to form a recess which varies in width, an elastic pad supported by said members and constructed and arranged to bridge the recess formed between said members, means for moving the heel support relatively to said members to cause the heel to engage the cover supported upon the pad and to distort the pad, whereby a portion of the cover is applied to the heel, and mechanism for forcing the members against the pad to apply other portions of the cover to the heel.
28. A heel covering machine having, in combination, a support for a heel, a pair of members spaced to provide a recess, an elastic pad mounted upon the members and arranged to bridge the recess, and means for moving the support relatively to the members to force the heel against a heel cover on the pad and to cause the pad to wrap the cover around the heel, said members being mounted for movement in timed relation to the support to distort the pad thereby to assist the same in applying the cover to the heel.
29. A heel covering machine having, in combination, a support for a heel, a pair of spaced members, a resilient pad supported by said members and arranged to support a heel cover, mechanism for effecting relative movement of the support and the pad in a predetermined path to cause the cover to be wrapped around the rear and portions of the sides of the heel, and means to move said members in paths disposed at substantial angles to said path to wrap the cover around other portions of the sides of the heel and upon the margins of the breast of the heel.
30. A heel covering machine having, in combination, a support for a heel, a pair of members spaced to form a recess, a resilient pad supported by said members and arranged to bridge the recess, said pad being constructed and arranged to support a heel cover, mechanism for moving the support relatively to the pad to cause the heel to force the pad into the recess and to distort the same thereby to apply the cover to the rear of the heel and to portions of the sides of the heel, and means for moving said member in paths disposed at substantial angles to the path of movement of the support to wrap the cover upon other portions of the sides of the heel and upon the margins of the breast of the heel.
31. A heel covering machine having, in combination, a support for a heel, a pair of members spaced from each other to form a recess, an elastic pad supported by said members, and means to force the heel against a cover placed upon the pad for causing the pad to be forced between said members, whereby the cover is wrapped around the rear and side surfaces of the heel and is inturned upon the breast of the heel.

WILLIAM P. DEVINE. 145
